UNITED STATES PATENT OFFICE.

SAMUEL TEECE, OF ENDERBY, BRITISH COLUMBIA, CANADA.

POISON-BOTTLE TOP.

1,367,841.

Specification of Letters Patent.

Patented Feb. 8, 1921.

Application filed March 27, 1920. Serial No. 369,436.

To all whom it may concern:

Be it known that I, SAMUEL TEECE, residing at Enderby, in the Province of British Columbia and Dominion of Canada, have 5 invented new and useful Improvements in Poison-Bottle Tops, of which the following is a specification.

This invention relates to improvements in bottle stoppers and particularly to stoppers 10 for use in connection with bottles containing poison or other dangerous liquids and is designed to warn the user of the character of the contents of the bottle.

Another object of the invention is the 15 provision of a device of the above character, by means of which a stopper may be secured against accidental displacement and which will render it necessary to manually release the stopper before the contents of the bottle 20 can be removed.

Another object of the invention is the provision of a device which is adjustable to 25 bottles of different sizes and which may be removably positioned so as to permit of its reuse upon other bottles when desired.

Another object of the invention is the provision of means for holding the stopper attached to the bottle as the liquid is poured or dropped therefrom, the stopper when in 30 this position, in no way interfering with such pouring or dropping.

Another object of the invention is the provision of a device of the above mentioned character which is simple in construction and cheap to manufacture and 35 which includes a securing band, cut from a single piece of material and bent to the desired configuration and a stopper cap likewise formed and detachably secured to the 40 stopper by means of an ordinary corkscrew.

The invention further consists in the following novel features and details of construction to be hereinafter more fully described and illustrated in the accompanying 45 drawings.

In the drawings:

Figure 1 is a side elevation of a portion of a bottle with the invention applied thereto.

Fig. 2 is a plan view of the same.

Fig. 3 is a side elevation showing the stopper removed, for the removal of the contents of the bottle.

Fig. 4 is an enlarged vertical section with the parts in the position shown in Fig. 1.

Fig. 5 is a detail perspective view of the

adjustable securing stand with its ends disconnected.

Fig. 6 is a detail perspective of the removable cap of the stopper.

Fig. 7 is a plan view of the blank of which 60 the adjustable securing band is formed.

Fig. 8 is a similar view of the stopper cap.

Referring to the drawings in detail, like characters of reference denote corresponding 65 parts in the several views.

In illustrating the invention, there is shown a portion of a bottle, which may be of any desired size and shape and which is designated at 10. The bottle may be supplied with the usual cork 11.

The invention, which is entirely separate from the bottle and cork may be purchased by the user and thereafter applied to the bottle and cork, or may be furnished with 75 a bottle as desired. It comprises a cap 12, which is cut from a single blank of material and is preferably circular in plan, having its marginal edges split inwardly as indicated at 13 to permit the surrounding 80 edge of the cap to be bent downwardly as shown, so as to fit over the bead 14 of the bottle mouth. The cap is also provided with a lip 15, which is formed by bending over upon itself a strip of material extending 85 from the edge of the cap. Located diametrically opposite this strip is a lug 16, which is likewise formed and this lug is provided with an opening 17, for a purpose herein-after apparent. The cap is secured in position through the medium of an ordinary cork-screw 18, which is inserted through an opening 19 in the cap 12, and is screwed into the stopper 11.

Surrounding the neck of the bottle below 95 the bead 14, is an adjustable band 20. This band is provided at one end with a loop 21, which is formed by bending inwardly toward one another, oppositely extending lugs 22. This band is adapted to receive a tongue 100 23 formed upon the opposite end of the band, the tongue being inserted through the loop 21 and bent over upon itself as shown. For adjusting the band 20 is an arm 24, which is bent to provide an inwardly extending finger 25, which is adapted to overlie the top of the bead 14 adjacent the bottle mouth. The arm 24 and finger 25 are provided with 105 openings for the passage of a vertically extending arm 26. The lower end of this arm 110

is provided with a loop 27 by means of which it is secured in position and its upper end is curved outwardly and has its extremity bent as shown at 28. This arm 26 is 5 passed through the openings 17 in the lug 16 so as to provide a sliding and pivotal mounting for the cap 12 and the bent extremity 28 of said arm prevents the removal of the cap.

Extending from the band 20 at a point 10 diametrically opposite the arm 24, is an arm 29, the latter being bent as shown to provide an inwardly extending finger 30 which engages over the upper edge of the bead 14, and which carries a spring catch 15 31, the extremity of which is inclined as shown at 32.

After the band 20 has been secured upon the bottle neck, the stopper 11 may be inserted within the mouth of the bottle, where- 20 upon the lip 15 will engage the inclined portion 32 of the spring catch and press the same outwardly, so that the catch 31 will spring over the upper surface of the lip to hold the stopper against accidental removal. 25 The stopper may be easily removed by springing the catch and removing the stopper, whereupon it may be slid along an arm 26 and moved pivotally to the position shown in Fig. 3, so that the contents of the 30 bottle may be easily removed. The invention may be readily removed from one bottle

and applied to another by straightening the tongue and sliding the same through the loop 21, so that a single device may be used in connection with various bottles.

35

The invention is susceptible of various changes in form, proportions and minor details of construction and the right is herein reserved to make such changes as properly fall within the scope of the appended claims.

40

Having thus described my invention what I claim as new is:—

1. The combination with a bottle and a stopper therefor, of a cap removably secured to the stopper, a vertically extending arm for slidably and pivotally securing the cap to the bottle, a compound curved extremity for preventing the removal of the cap from the arm, and means including a spring catch for holding the cap against accidental move- 45 ment.

2. The combination with a bottle and a stopper therefor, of a cap removably secured to the stopper, and means for removably securing the cap to the bottle, said means being formed from a single piece of material and comprising an adjustable band, an arm extending from said band, and a spring catch also extending above the band for engage- 55 ment with the stopper cap.

60

In testimony whereof I affix my signature.
SAMUEL TEECE.
